(57) **CLAIM**

The ornamental design for a handle for a pull-up handle as shown and described.

DESCRIPTION

FIG. 1 is a perspective view from the top of a handle for pull-up handle according to the design;

FIG. 2 is a perspective view from the bottom of the handle for pull-up handle of FIG. 1;

FIG. 3 is a front view of the handle for pull-up handle of FIG. 1;

FIG. 4 is a rear view of the handle for pull-up handle of FIG. 1;

FIG. 5 is a first side view of the handle for pull-up handle of FIG. 1;

FIG. 6 is a second side view of the handle for pull-up handle of FIG. 1 of;

FIG. 7 is a top plan view of the handle for pull-up handle of FIG. 1; and,

FIG. 8 is a bottom plan view of the handle for pull-up handle of FIG. 1.

The broken lines forming a plurality of hexagons along the exterior surface depict portions of the handle that form no part of the claimed design.
